UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 15, 1921. Serial No. 452,433.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to a device in the 10 nature of an accessory or attachment to be placed at the front of a typewriting machine, or a combined typewriting and computing machine, as a means for enabling an operator to assemble with celerity work- 15 sheets and intervening carbon-sheets.

As herein disclosed, the device is in the nature of a box-like structure, and, preferably, comprises two compartments side by side and divided by a partition. These compartments may be open at their outer ends 20 and a little shorter than the work-sheets to be used therein, so that the packs or piles of the latter will protrude sufficiently to be easily accessible.

25 The device may also comprise a jogging tablet or table which may project therefrom or may, at least partially, overlie the compartments. It will be evident that the latter arrangement tends to make the device 30 more compact. The location of the jogging table close to the compartments for holding the work-sheets enables the operator to pick up work-sheets and jog them into register without moving the same away from the 35 compartments to any great extent.

The device may be supported at the front 40 of the machine, and preferably this is done by attaching it to the upper ends of the legs or standards of a stand, such as that used for combined typewriting and computing machines, so that it will occupy a position at the front of the keyboard at a convenient height.

45 The device is especially designed for writing small bills of which one carbon copy is to be made in each case, but the machine may also be used for other purposes.

When the invention is to be used, a package of work-sheets is placed in each of the compartments, with the ends of the work-sheets projecting from the ends thereof. The operator may then pick up two work-sheets and place them with a carbon-sheet therebetween upon the assembling or jogging table, and then jog the sheets together 55 to bring them into register before inserting them in the machine. Preferably, the assembling or jogging table is provided with a ledge against which work-sheets may be laid, to place them in approximate register 60 before jogging them into final position on the table.

After the items are typed upon the work-sheets, the latter are removed from the machine, and the carbon-sheet therebetween is 65 removed, so that it may be used with another set of work-sheets.

70 Preferably, the assembling or jogging table extends forwardly from the front wall of the holders, but, if desired, it may be positioned otherwise; for example, it may partially overlie the compartments.

Inasmuch as the upper portions of the work-sheets are usually occupied by printed headings, and nothing is to be typed upon 75 that portion of the sheets, use may be made of a carbon-sheet of substantially less height than the work-sheets, and, to enable the carbon-sheet to be readily removed from its position between work-sheets upon which 80 typing has been effected, the carbon-sheet may be made of greater length than the work-sheets, so that it may be easily grasped and withdrawn therefrom. The operator may assemble two work-sheets and one carbon-sheet of the form described, by placing a work-sheet on the jogging table, placing a carbon-sheet thereon and then another work-sheet on the opposite side of the carbon-sheet, as a preliminary step to bring 85 the sheets and carbon-sheet into register.

Such assembling of the work-sheets and carbon-sheet may also be effected by laying the carbon upon the top sheet in one of the

compartments, withdrawing this work-sheet with the carbon thereon, placing another work-sheet on the top of the carbon-sheet, and bringing the sheets into register 5 on the jogging or assembling table. It will be seen that the work-sheet on which the carbon-sheet has been placed may readily be engaged by the thumb, since the carbon is of less height than the work-sheet. In 10 order to facilitate the withdrawal of work-sheets from the compartments, the operator may use suitable devices, such as rubber bands or cots upon the thumbs, so that by placing the thumbs on the exposed ends 15 of the upper work-sheets there will be sufficient frictional contact to withdraw the same from said compartments.

In case the assembling or jogging table overlies the compartments, it may be shortened at its right-hand end for convenience in placing the carbon-sheet upon the upper sheet in the right-hand compartment. Upon the removal of the work-sheets after 25 typing thereon, the carbon-sheet therebetween may be readily withdrawn by grasping the end which, due to the fact that the carbon-sheet is of greater length than the work-sheets, extends from the latter.

Other features and advantages will hereinafter appear.

In the accompanying drawings,

Figure 1 is a plan view, showing my invention applied to so much of an Underwood-Hanson bookkeeping machine as is necessary for purpose of illustration.

Figure 2 is a side view of a portion of the machine, showing two work-sheets and a carbon-sheet therebetween brought into register on the jogging or assembling table.

Figure 3 is a view, as seen at the front of the machine, of the work-sheets and carbon-sheet therebetween, shown on the assembling table of Figure 2.

Figure 4 is a perspective view of the form of the invention shown in Figure 1.

Figure 5 is a perspective view of a modified form of the invention.

The Underwood bookkeeping machine to which the invention is applied, as herein disclosed, comprises a typewriter 11 having alphabet-keys 12 and number-keys 13, and a computing element with a casing 14, on which the typewriter 11 rests. In the illustrated construction, the casing 14, accordingly, constitutes the base of the frame of the combined typewriting and computing machine. The casing 14 may be supported on a table 15, forming part of a stand 16, the table 15 having the usual rim or rib 17 from which extend brackets 18 overlying standards 19 of the typewriter stand and secured thereto by any suitable means, such as screws 20 extending through perforations in brackets 18, and threaded into the 55 upper parts of standards 19. The brackets

18 are so shaped that the lower edge of the rim 17 is maintained substantially level with the tops of the standards.

According to the present invention, a box-like work-holder 21 is supported at the 70 front of the machine, so that work-sheets or cards placed therein may be readily accessible to the operator. In order that the work-holder 21 may project as little as possible from the front of the machine, and at the 75 same time neither obstruct the view of the registers 22 in the front of the casing 14, nor interfere with the operation of the error-keys 23 and the star-keys 24, it is placed with its bottom wall 25 extending over the 80 rib 17 at the front of the stand top or table 15. To support the work-holder 21 in position as just described, without making any change in the structure of the combined typewriting and computing machine, brackets 26 may be secured to the bottom of the holder 21 by any suitable means, such as screws 27, and to the tops of the front standards 19 by means of the screws 20. Inasmuch as the tops of the standards 19 lie 85 below the bottom wall 25 of the work-holder, the brackets 26 are bent downwardly, preferably close to the point of attachment to the bottom wall 25, and are then bent 90 at another point so as to extend substantially horizontally to the tops of the standards 19. The brackets 26 may be shaped so that, in order to give the proper height to the work-holder 21, the brackets 26 may be placed either on top of brackets 18 or beneath the same, the openings in the ends of the two sets of brackets being in register, so that both may be fastened on the standards 19 by the screws 20.

As shown in Figure 4, the work-holder has a back wall 28 and a front wall 29, and is divided into two compartments by a wall or partition 30, the compartments being open at their outer ends so that the ends of packs or piles of work-sheets 31 placed in said compartments may extend beyond the ends of said compartments to facilitate removal of individual sheets. The front wall 29 may also be cut away at its ends, so as to render the ends of the piles or packs of work-sheets more easily accessible.

Provision may also be made of an assembling or jogging table 32, which preferably extends forwardly from the upper edge of the front wall 29, and is provided with a ledge 33 at its forward edge. In practice, a work-sheet or card 31 is taken from each compartment and placed on the table 32 with a carbon-sheet 34 lying therebetween. The work-sheets and intervening carbon-sheets may be brought into approximate alignment by engagement with the ledge 33, and may then be raised and brought to final adjusted positions relative to each other by 125 130

resting the lower edges of the work-sheets and carbon-sheet on the table 32 and if necessary jogging the sheets thereon. The assembled work-sheets and carbon-sheet 5 may then be placed in the machine and typing effected thereon. After the items have been typed on the work-sheets they are removed from the machine and the carbon is withdrawn so that it may be used 10 with another set of work-sheets.

Preferably the carbon-sheet 34 is of substantially less height than the work-sheets, inasmuch as the upper portions of the latter are usually occupied by printed headings and nothing is to be typed upon said portions. It is desirable, also, that the carbon-sheet be of sufficient length to project from the assembled work-sheets at one side, so that, after typing has been effected 15 and the work-sheets withdrawn from the machine, it may readily be pulled out ready for use with other sheets. The adjusted position of such a carbon-sheet between two work-sheets is shown in Figure 3.

20 25 A convenient method of withdrawing work-sheets from the two compartments consists in placing the thumb of either hand on the top card or sheet in the corresponding compartment and sliding the sheet end- 30 wise by the frictional contact of the thumb therewith until the sheet may be grasped between the thumb and one or more fingers. To insure suitable frictional contact between the thumbs and the work-sheets, suitable means may be provided, such as rubber bands or cots placed on the thumbs.

In assembling two work-sheets thus withdrawn from the compartments of the work-holder, one may be placed on the table 32, 40 a carbon-sheet laid thereon approximately in proper position, and the other work-sheet placed thereon, approximate registry of the sheets being obtained by placing the same against the ledge 33. The work-sheets and 45 intervening carbon-sheet may then, if desired, be jogged on the table 32, to bring the edges, shown at the left in Figure 3, into register, and the work-sheets and intervening carbon-sheet may thereafter be turned 50 into the general position shown in Figures 2 and 3, and jogged on the table, so as to bring the sheets into register as indicated in Figure 3, the portions of the sheets extending above the carbon-sheet enabling the 55 work-sheets 31 to be held at their side edges to permit such manipulation. The assembled work-sheets and carbon-sheet may then be inserted in the machine and items typed thereon. After such typing has been completed, the assembled sheets may be removed 60 from the machine, and the carbon-sheet which projects at the right, as shown in Figure 3, may be withdrawn to enable its use with another set of work-sheets.

65 The work-sheets and carbon-sheet may

also be assembled by placing the carbon-sheet on the top work-sheet in one of the compartments, preferably the one at the right, and removing the sheet by engagement of the thumb with a portion of the sheet extending above the upper edge of the carbon-sheet. This work-sheet and the carbon-sheet held in position thereon may be placed on the table 32, another sheet placed thereon, and the sheets then brought into 70 registry by the method previously described, and, upon removal of the work-sheets and carbon-sheet from the machine, the carbon-sheet, after withdrawal from the work-sheets, may be placed again in the right 75 hand compartment.

In the modified form of the attachment or accessory, shown in Figure 5, the assembling or jogging table, which is there designated 35, extends over the compartments of 80 the work-holder, whereby a more compact form of the attachment is obtained. If desired, provision may be made of a ledge 36, preferably at the forward edge of said table 85 90 95 100 105 110 115 120 125 130 35, to facilitate the placing of the sheets in approximate registry before submitting them to the jogging action on the table 35. The table 35, extending, as it does, over the compartments of the holder 21, tends to interfere with the placing of the carbon-sheet on the top of a pile or pack of work-sheets in either one of said compartments, and, to obviate this difficulty, the table may be shortened at the end overlying the compartment in which the carbon-sheet is to be placed, in this case the right-hand compartment.

Although the accessory or attachment is herein illustrated and described as being applied to a combined typewriting and computing machine, it is recognized that the accessory may usefully be employed in connection with a typewriting machine which is not provided with computing mechanism. In such a case, the accessory is located in front of and closely adjacent to the keyboard of the typewriter and at the level of the base of the typewriter frame, it being understood that by the base of the typewriter frame is meant the portion of the frame adjacent to the stand or other support upon which the machine rests. The position of the accessory relative to the keyboard of the typewriter is, therefore, similar to its position relative to the keyboard of the combined typewriting and computing machine as shown in the drawing, so that the holder greatly facilitates the assembly of work-sheets and carbon-sheets and their insertion into the typewriter, and does not obstruct the view of the typewriter keys nor interfere with their operation.

Variations may be resorted to within the scope of the invention, and portions of the improvements may be used without others.

Having thus described my invention, I claim:

1. An accessory for a machine comprising typewriter mechanism, said accessory including a work-sheet holder having two compartments arranged in substantial alignment from side to side of the machine and separated from each other by a partition located centrally in the holder, and means for supporting the holder in front of and closely adjacent to the keyboard of the machine with the partition also located substantially centrally of the machine, so as to cause the compartments of the holder to be so positioned that a work-sheet can be conveniently withdrawn from either of said compartments for insertion into the machine.

2. An accessory for a machine comprising typewriter mechanism, said accessory including a work-sheet holder having two compartments located on opposite sides of the center line of the machine in alignment with each other from side to side of the machine and so constructed that sheets may be withdrawn by the operator from one of said compartments in one direction laterally of the machine with one hand and from the other compartment in the opposite direction laterally of the machine with the other hand, and means for supporting the holder in front of and closely adjacent to the keyboard of the machine.

3. An accessory for a machine comprising typewriter mechanism, said accessory including a holder having a compartment for containing work-sheets, means for supporting the holder in front of and closely adjacent to the keyboard of the machine, and a table mounted on the holder adjacent to said compartment and formed to present a surface extending laterally of the typewriter, on which the work-sheets may be jogged to bring them into register.

4. An accessory for a machine comprising typewriter mechanism, said accessory including a work-sheet holder having two compartments separated by a partition and open at their outer ends to enable work-sheets to be slidably withdrawn therefrom laterally of the machine, means for supporting the holder in front of and closely adjacent to the keyboard of the machine, and a table fixed to said holder and formed to present a surface extending laterally of the machine adjacent to said compartments, on which the work-sheets may be jogged to bring them into register.

5. An accessory for a machine comprising typewriter mechanism, said accessory including a work-sheet holder having front and rear walls, a table located adjacent to the front wall of the holder and at substantially the level of the top of said wall and being formed to present a surface ex-

tending laterally of the machine, on which the work-sheets may be jogged to bring them into register, and means for supporting the holder and the table in front of and closely adjacent to the keyboard of the machine.

6. A typewriter accessory consisting of a work-sheet holder having front and rear walls, a substantially horizontal table to co-operate therewith, extending laterally of the typewriter at the top of one of said walls and formed and arranged to present a surface on which work-sheets may be conveniently placed as they are withdrawn from the holder and against which the work-sheets may be jogged to bring them into register with each other, and a ledge against which the sheets as they are placed on the table may be brought into approximate register preparatory to the jogging of them into exact register, said ledge extending longitudinally of said table forwardly of said surface.

7. In an apparatus of the class described, supporting means for a machine comprising typewriter mechanism, said supporting means including a stand having a top with brackets extending therefrom at the front and on opposite sides thereof and standards on the upper ends of which said brackets rest, a work-sheet holder having brackets so constructed that, when the holder is suitably positioned for use in front of and closely adjacent to the keyboard of the machine, the ends of the last-mentioned brackets will lie over the standards at the front of the machine, and means for securing both sets of brackets to the standards on which they rest.

8. A typewriter accessory consisting of a work-sheet holder comprising front and rear walls and being divided into two compartments each of which is open at its ends to permit work-sheets to be slidably withdrawn therefrom, the front wall of said holder being shortened at each end so as to be spaced inwardly from the ends of the holder and to enable the thumbs to be thrust laterally of the holder into engagement with the work-sheets in the compartments to withdraw the work-sheets endwise from the compartments, and an assembling table extending along said holder.

9. A typewriter accessory consisting of a work-sheet holder having two compartments arranged end to end in substantial alignment transversely of the typewriter and open at their outer ends, and an assembling table at the top of said compartments in fixed relation to said holder and being formed to present a plane upper surface against which the work-sheets may be jogged to bring them into register with each other.

10. In an apparatus of the class described,

supporting means for a machine, comprising typewriting mechanism, said supporting means including a stand having brackets at the upper right and left sides of the front thereof, a work-sheet holder having a base-piece extending lengthwise of the front of the stand forward of the position assumed by the keyboard of the machine when the

latter is in place on the stand, and arms connected to said base-piece and to the 10 brackets on the stand for holding the sheet-holder.
